UNITED STATES PATENT OFFICE.

GEORGE LANE, OF POUGHKEEPSIE, NEW YORK, ASSIGNOR TO LANE BROS. CO., OF
POUGHKEEPSIE, NEW YORK, A JOINT-STOCK ASSOCIATION OF NEW YORK.

LIFTING-JACK.

1,227,915.

Specification of Letters Patent. Patented May 29, 1917.

Application filed November 17, 1916. Serial No. 131,911.

To all whom it may concern:

Be it known that I, GEORGE LANE, a citizen of the United States, and resident of Poughkeepsie, New York, have invented certain new and useful Improvements in Lifting-Jacks, of which the following is a specification.

My present invention relates to improvements in lifting jacks adapted more especially for use in connection with motor vehicles, though by no means limited to such use, and is designed as an improvement or modification of the jack which forms the subject of Letters Patent of the United States, No. 1,122,235, dated December 22nd, 1914.

The invention has among its objects the following to wit:

To dispose of the protruding bell cranks and C spring, which project outside and rearwardly of the case and which are thus liable to damage.

To provide an automatic drop for the lift bar when not under load, as in lowering an automobile axle after the wheel has touched the ground, so that when there is no longer necessity for lowering the jack, notch by notch, the lift bar will drop automatically.

To provide a design in which the mechanism effecting the lifting and lowering operations are more completely inclosed and inaccessible and free from being tampered with.

To include an operating button for the shift rod.

With these objects in view the invention includes the novel features of construction and arrangement and combination of parts hereinafter described and particularly defined by the appended claims.

Several embodiments of my invention are illustrated in the accompanying drawings, in which,

Figure 1 is a side elevation of a jack embodying my invention with the casing open on one side to show the operating mechanism.

Fig. 2 is a view on a larger scale with the parts in position to elevate the lifting bar.

Fig. 3 is a view similar to Fig. 2 with the parts in position to lower the lifting bar step by step.

Fig. 4 is a similar view illustrating the action of the pawls when the load on the lifting bar is removed and it drops automatically.

Fig. 5 is a detail view of the actuating lever and handle bar (partly broken away) viewed from the side opposite to that of the preceding figures. 60

Fig. 6 is a longitudinal sectional view of the inner end of the handle bar.

Figs. 7 and 8 are detail views of the actuating button.

Figs. 9 to 11 are detail views of a modification. 65

Referring by reference characters to these drawings the numeral 1 designates the base, 2 the standard and 3 the lifting bar which may be constructed and arranged as described in my aforesaid patent, the lifting bar having on one face the ratchet teeth 3^a and at its upper end a suitable head 3^b.

The holding pawl 4 is pivotally supported in a suitable manner upon the standard 75 while the lifting pawl 5 is similarly mounted upon the inner end of the lifting or actuating lever 6.

The actuating lever 6 is provided with a socket 6^a to detachably receive a hand lever 80 and said actuating lever is pivoted at 10 between the side plates 8 suitably secured to the standard and forming a housing or casing for the actuating lever, pawls and controlling mechanism hereinafter described. 85

The actuating lever supports a carrier for a pawl equalizing device or lever 9, which carrier is movable longitudinally of the actuating lever or in a direction toward and from the lifting bar and pawls. 90

I prefer to make this carrier in the shape of a yoke or U-shaped member 11, one arm 11^a of which is pivotally supported by the actuating lever, while the other arm 11^b extends transversely through an open space 6^b 95 in the actuating lever so as to be capable of being swung in said space toward and away from the lifting bar.

A spring 12 acting on this yoke tends to keep the arm 11^b normally forced away from the lifting bar, the extent of movement being determined by the wall of the opening in the actuating lever through which the yoke part or bar 11^b extends. 100

To the extremity of this yoke member or bar 11^b is pivotally connected an equalizing device or lever 9 which I prefer to form in the shape of a cross head or bar having its intermediate portion pivoted to the arm 11^b and its extremities connected by springs 13 110 and 14 to the pawls 5 and 4, respectively.

As hereinbefore stated, the carrier is

pressed by its spring normally away from the lifting or ratchet bar, carrying with it the equalizer which, by its connection with the pawls through the springs 13 and 14, 5 tends to hold these pawls swung backward out of engagement with the teeth of the ratchet bar, the backward movement of the pawl 5 being limited by a stop or abutment 15 on one of the side plates, and the backward movement of the pawl 4 being limited 10 by providing it with a tail 16 which contacts with the rear wall member 2^b of the standard, (as shown in Fig. 3).

Any suitable means may, however, be provided for limiting this backward movement 15 of the pawls.

Normally therefore the pawls and equalizing device are in position for lowering the lifting bar, but before explaining the lowering action I will describe how the lifting 20 action is effected.

The handle bar 7 is designed to be locked in position in the socket of the actuating lever by a spring pawl 7^a. The handle bar 25 carries at one side a longitudinally movable rod 17 suitably held in position, as for instance, by having its front end doubled backward upon itself, as indicated at 17^a, (Fig. 6), said end being guided in an elongated opening 17^b in the end of the handle bar. The rear end of the rod is connected 30 to a suitable actuating device, preferably in the form of a button, indicated at 18. This consists of a disk having a hub 18^a journaled upon a pin 19 secured to the handle bar, said disk having an annular flange 18^b which is cut away or interrupted for a suitable distance as indicated at 18^c. Through the opening thus formed the rear end of the rod 35 is passed and is eccentrically connected to the disk or button, preferably by having its end turned outwardly and passed through an opening, as indicated at 17^e. The disk or button is provided with suitable means 40 for conveniently turning it, such for instance, as wings 18^d. The ends of the flange 18^b contacting with the rod 17, as the button is turned, serve as stops for limiting the movement of the button in either direction, and the arrangement is such that the 45 rod is automatically locked in its forward position by reason of the fact that its point of pivotal connection with the button passes the center or axis of the button, as shown in Fig. 5, and the lower dotted lines, Fig. 1.

This button with its wings and eccentric connection with the rod provides a convenient leverage for multiplying the force and thrusting the rod forward, and also 50 affords convenient means for determining whether the jack is set for raising or lowering by providing convenient markings on the button to register with the suitable indication on the handle bar.

55 The forward end of the rod passes into a

groove 6^c in the lower side wall of the actuating lever in line with the carrier or yoke bar 11^b and when the handle bar is in position in the actuating lever socket and the rod 17 has been pressed forward by the proper rotation of the button the carrier is pushed forward against tension of its spring and both springs 13 and 14 are placed under compression, whereby they tend to force the pawls into engagement with the teeth of the lifting bar, as shown in Figs. 1 and 2. Movement of the actuating lever up and down then causes the pawls to alternately engage and lift the ratchet bar, the idle pawl riding over the teeth of the bar as the working pawl is effecting the lifting or holding action.

The lifting bar having been raised to the proper height and it being desired to lower the load the button is turned to retract the rod 17, (as indicated by the upper dotted lines Fig. 1). This allows the carrier to move backward under the tension of its spring, which is strong enough to place springs 13 and 14 under tension. The equalizing member or cross bar has a rearwardly extended or widened portion, provided with a slot or guide 9^a which when the equalizer is forced backwardly by the carrier spring engages with a pin or projection 20 carried by one of the side plates.

When the equalizer is thus engaged by the pin it is caused to rock as the actuating lever is moved up and down, due to the fact that the point of pivotal connection of the equalizer to the carrier is in advance of the pin 20.

Supposing at the completion of the lifting action the jack has come to rest with the hand lever depressed and the upper pawl 105 retaining the load, (as shown in full lines, Fig. 3) and the lowering action to be desired, the backward movement of the rod 17 before referred to allows the spring to force the carrier and yoke backward.

The engagement of the pin 20 with the slot 9^a insures the positioning of the equalizer to apply tension to the springs 13 and 14 alternately. In other words, with the hand lever depressed and the lifting pawl 115 5 in engagement with the ratchet bar the upper end of the equalizer is rocked forward by contact with pin 20 with the upper wall of the slot, whereby spring 13 is relieved of tension, while the lower end of the 120 equalizer is swung backward away from pawl 4, placing tension on spring 14 connected thereto. Raising of the lifting bar under the load rocks the equalizer in a reverse direction, (as indicated by dotted lines 125 Fig. 3) its upper end moving outwardly and applying tension to spring 13, while its lower end moves inwardly until spring 14 acts as a compression spring, or its coils are closed, when it forces pawl 4 into engage- 130

ment with one of the teeth of the ratchet bar. As soon as the load is supported by pawl 4 spring 13 pulls pawl 5 out of engagement with the ratchet bar.

This operation is repeated as long as the lifting bar is being lowered under a load, the rocking movement of the equalizer alternately applying tension to one spring and compression to the other.

10 It is desirable in a jack of this character to make provision for the dropping of the lifting bar automatically when the load is released.

For example when an automobile axle is being lowered it is of advantage to have the lifting bar drop automatically as soon as the axle is lowered sufficiently to allow the tire to contact with the ground so as to avoid the necessity of working the handle up and down to lower the lifting bar the balance of the distance. My improved construction provides for this as it will be observed that when the actuating lever and handle bar during the lowering action are 25 in neutral position both springs 13 and 14 are under slight tension tending to pull both pawls backwardly. This tension is so slight that during the normal lowering action it is ineffective to pull the pawl which 30 is carrying the load out of engagement with the teeth of the ratchet bar bearing thereon by reason of the frictional engagement of the respective parts under the load.

When the load is released, however, the 35 tension of the spring when the operating lever is in neutral position, is sufficient to overcome this friction and hence the pawl supporting the lifting bar is drawn out of engagement with the tooth and the bar 40 drops.

Instead of using a swinging carrier for the equalizer, I may use a sliding carrier as shown in Figs. 9 to 11.

In this modification, I make the equalizer 45 in the form of a pair of cross heads or bars 9^x connected together at top and bottom by spacing posts α .

These bars lie on opposite sides of the actuating lever 6^x and the latter has a longitudinal slot 6^z through which passes a sliding pivot pin 9^b having its ends connected to said bars or members 9^x, this pin forming the carrier for the equalizer.

The actuating lever 6^x has a longitudinally extended recess in which is seated a coiled spring 12^x which tends to keep the carrier normally pressed away from the lifting bar and pawls to the limit allowed by the slot 6^z.

60 When the carrier is in this position the parts are set for lowering the ratchet bar as illustrated in Fig. 3. The carrier may be forced forward against the tension of the spring by a rod, such as shown at 7, 65 Fig. 1, or any other suitable means.

The spacer posts are preferably provided with grooves α' around which the ends of the springs 13^x may be hooked.

What I claim is:—

1. A jack comprising a standard, a lifting bar, an actuating lever, a lifting pawl and a holding pawl coöperating with said lifting bar, a carrier movable longitudinally of the actuating lever, a spring normally pushing said carrier away from the lifting bar, an equalizing member pivotally supported from said carrier, and having its ends resiliently connected respectively to said pawls, and means for pressing said carrier toward the lifting bar. 20

2. A lifting jack comprising a standard, a lifting bar, an actuating lever, a lifting pawl and a holding pawl coöperating with said lifting bar, a carrier on the actuating lever movable toward and from the lifting bar, an equalizing device pivotally supported from the carrier and having portions resiliently connected with said pawls, a spring normally pressing the carrier away from the pawls, means for pressing said carrier toward the lifting bar against the tension of said spring to position the pawls for a step by step lifting action, and means operative when the carrier is pressed away from the lifting bar for rendering said pawls effective for step by step lowering of the lifting bar. 30

3. A jack comprising a standard, a lifting bar, an actuating lever, a lifting pawl and a holding pawl coöperating with said lifting bar, a carrier movable longitudinally of the actuating lever to either of two positions, an equalizing member pivotally mounted on said carrier and having upper and lower portions resiliently connected to 105 said pawls, said equalizing device when in one position applying compression to said springs, and means acting on said equalizer when in its other position for applying compression and tension to said springs alternately at the extremities of the up and down movement of the actuating lever. 110

4. A jack comprising a standard, a lifting bar, an actuating lever, a lifting pawl and a holding pawl coöperating with said 115 lifting bar, a carrier movable longitudinally of the actuating lever, an equalizing lever pivotally supported from the carrier, springs connecting said lever with said pawls, means for shifting said carrier into 120 either of two determined positions, said equalizing lever having a guide extending transversely thereinto from one side, and a projection on the standard adapted to engage the guide when the lever is in one of 125 said determined positions.

5. A jack comprising a standard, a lifting bar, an actuating lever, a lifting pawl and a holding pawl coöperating with said lifting bar, a carrier yoke having an arm 130

5 pivotally supported by said actuating lever and another arm movable longitudinally of said actuating lever, an equalizing lever pivotally connected to said other arm, springs 10 connecting said equalizing lever with said pawls, means for swinging said yoke to carry the lever bodily into either of two determined positions, said equalizing lever having an open slot in one side, and a fixed 15 projection adapted to engage said slot in one of said determined positions.

6. In a lifting jack, a standard, a lifting bar, an actuating lever, lifting and holding pawls, a carrier on the actuating lever movable toward and from the lifting bar, a 15 spring pressing it normally away from the lifting bar, an equalizing lever having its ends resiliently connected with said pawls, an operating rod movable longitudinally of 20 the actuating lever and having an end adapted to engage said carrier, and eccentric means for actuating said rod.

7. In a lifting jack, a standard, a lifting bar guided therein, a casing including parallel side plates, an actuating lever pivoted between said side plates, lifting and holding pawls coöperating with said lifting bar, lever means lying against the side of said actuating lever, and having upper and lower 25 arms connected respectively to said pawls, a fulcrum for said lever, means movably carried by said actuating lever, means for moving said fulcrum to either of two positions to determine the action of the pawls 30 in raising or lowering the lifting bar, and contact means on one of the side plates for coöperating with the lever means when the fulcrum is in one position.

8. In a lifting jack, a standard, a lifting 40 bar guided therein, a casing including parallel side walls, an actuating lever pivoted between said side plates, lifting and holding pawls coöperating with said lifting bar, lever means lying in proximity to the side of 45 the actuating lever and having upper and lower arms connected respectively to said pawls, a fulcrum for said lever means shiftable lengthwise of said actuating lever to either of two determined positions, means 50 for moving said fulcrum to either position to determine the action of the pawls in rais-

ing or lowering the lifting bar, said lever means including two rearwardly extending parts with a space between, and a stud on one of the side walls to contact with said 55 rearwardly extending parts when the fulcrum is shifted to lowering position.

9. A jack comprising a standard, a lifting bar, an actuating lever, a handle detachably engaging the same, a lifting pawl and a 60 holding pawl coöperating with the lifting bar, a carrier movable longitudinally of the operating lever, a yielding connection between the carrier and each pawl, and means for moving the carrier mounted on said detachable handle, substantially as described. 65

10. A jack comprising a standard, a lifting bar, an actuating lever, a lifting pawl and a holding pawl coöperating with the lifting bar, a carrier supported by and movable longitudinally of the actuating lever to either of two determined positions for determining the upward or downward movement of the lifting bar and resilient means connecting said carrier with the pawls. 70 75

11. A jack comprising a standard, a lifting bar, an actuating lever, a detachable handle for operating the same, a lifting pawl and a holding pawl coöperating with the lifting bar, a carrier movably longitudinally of the operating lever, a spring for moving the carrier in one direction, manually operated means mounted on the detachable handle for moving it in the other direction, and a yielding connection between 80 85 the carrier and each pawl.

12. In a lifting jack, a standard, a lifting bar, an actuating member, lifting and holding pawls, a carrier on the actuating member movable toward and from the lifting bar, a spring pressing it normally away from the lifting bar, an equalizing lever having its ends resiliently connected with said pawls and operable by said carrier, a handle detachably engaging said actuating 90 member and means carried by said detachable handle for operating the carrier to adjust the said equalizing lever from a point distant therefrom, substantially as described. 95

In testimony whereof, I affix my signature. 100

GEORGE LANE.
